UNITED STATES PATENT OFFICE.

LOUIS BLESSING, OF JACKSON, MICHIGAN.

RAIL-CLAMP.

1,094,518.

Specification of Letters Patent. Patented Apr. 28, 1914.

Application filed November 26, 1913. Serial No. 803,120.

To all whom it may concern:

Be it known that I, LOUIS BLESSING, a citizen of the United States of America, residing at Jackson, in the county of Jackson and State of Michigan, have invented certain new and useful Improvements in Rail-Clamps, of which the following is a specification, reference being had therein to the accompanying drawings.

1. In securing track rails to ties of cementitious material or other non-penetrable substances, where it is necessary to use something beside the ordinary track spike, it is desirable that the rail be held by means that 15 resists any tendency to creep or move laterally of the tie and longitudinally of the rail under the vibrations of a rolling load. It is also advantageous that such holding means be readily applicable and afford a yielding 20 cushioning support to the rail.

This invention relates to a rail fastener and to an arrangement thereof whereby, although it is readily placed in position, it cannot work loose.

25 Another feature of the invention is the cushioning support and holding pressure inserted upon the rail.

The invention consists in the matters hereinafter set forth and more particularly 30 pointed out in the appended claims.

In the drawings, Figure 1 is a view showing a tie with rail seat and rail thereon provided with rail fasteners or clamps that embody features of the invention, the view being partially broken away; Fig. 2 is a view 35 in detail of one form of rail seat; Fig. 3 is a view in detail of a seat cushion; Fig. 4 is a view in detail of a tie with the seat and seat cushion removed; Fig. 5 shows details of a 40 fastening bolt and retaining tube; and Fig. 6 is a view in detail of a clamping head.

Referring to the drawings a tie 1 of any 45 approved material, such as reinforced concrete or the like has a transverse gain near each end in which a cushion 2 of sheet fiber or the like may be laid. A rail seat 3 rests upon the cushion and is retained against movement transversely to the tie by marginal depending flanges 4. The cushion may 50 rest on the top of the tie and the rail seat hold it in position, if preferred, or other variations in the cushion and seat may be made if desired. A pair of oppositely disposed projections or ribs 5 are formed each 55 near the corner of and on the upper face of the seat.

A pair of holding members 6 are secured to the body of the seat at their lower ends in such way that their upper portions may be swung up alongside the faces of the tie 60 and the depending flanges 4 of the seat into operative relation to the base flanges 7 of an applied track rail 8. Preferably the holding members are bent between their ends to form arms 9 that extend into a 65 socket tube 10 embedded in the tie below the seat in substantially parallel relation to the rail, or the tube may be omitted if preferred.

A clamping head 11 that is longitudinally movable on the upwardly extending portions of the holding members 6 has a projecting lug 12 whose under face is adapted to conform to and rest on the upper face of the base flange 7 of the rail when the holding member is in operative position. A 75 suitably disposed slot 13 in the under face of the clamp receives the adjacent projection 5 of the rail seat and thereby confines the clamp as well as the holding member 6 from movement longitudinally of the rail 80 and transversely of the tie. A nut 14 that engages the screwthreaded outer end portion of the holding member 6 forces a split or spring washer 15 against the clamp 11 and thereby causes the latter to exert a yielding 85 pressure against the rail. Or the nut 14 may bear directly against the clamp, but the cushioning effect of the spring washer forcing the rail and seat against the cushion on the tie produces better results as it effectively eliminates the tendency of the 90 co-operating members to work apart from vibration.

One advantage of the fastening means is the ease of application which coupled with 95 its simplicity and its positiveness of action makes it extremely effective. Because of the cushioning support to the rail and the elastic clamping pressure, the parts do not tend to work loose or to crystallize and 100 thereby weaken themselves under strain.

Obviously, changes in the details of construction may be made without departing from the spirit of my invention and I do not care to limit myself to any particular 105 form or arrangement of parts.

What I claim is:—

1. The combination with a railway tie and track seat thereon, of rail fastening members each attached to the body of the 110 tie to swing into operative relation to the rail and seat, rail clamps longitudinally ad-

justable on the holding members adapted to interlock with the rail seat against lateral movement and to engage over the rail, and means engaging the members for holding the rail clamps on the seat and rail.

2. The combination with a railway tie and a rail seat thereon, of holding members each secured to the tie body beneath the seat and adapted to swing into operative relation to the rail seat, and a track rail applied thereto, clamping members adjustably secured on the holding members and adapted to interlock with the rail seat against lateral movement, and means detachably engaging the holding members for forcing the clamping members to seat.

3. The combination with a railway tie, a rail seat thereon and a track rail resting on the seat, of a pair of holding members pivotally secured at the lower ends thereof to the track tie to swing into operative relation to the track seat and rail, clamping means on the holding members adapted to interlock with the rail seat of the rail against lateral movement, and means engaging the holding members and yieldingly forcing the clamping means against the rail and seat.

4. The combination of a track tie of cementitious material, a rail seat on the tie, a cushion for the seat between the latter and the tie and a track rail resting on the seat, of holding members each engaging a transverse opening in the tie below the seat with the outer portion adapted to swing into operative relation to the tie, and seat, a clamp on each holder adapted to engage a projection on the seat whereby lateral movement of the clamp is prevented and to hook over the base and flange of an applied rail, and

means on the holding members for forcing the clamps into position.

5. The combination with a railway tie of cementitious material, a seat cushion thereon, a rail seat resting on the cushion and having a pair of oppositely disposed longitudinally arranged projections on its face, and a track rail resting on the seat between the projections, of holding members each bent between its ends with the lower portion engaging in a transverse opening of the tie below the rail and with the outer portions extending obliquely past the seat and rail flange, a clamp on each holding member adapted to hook over the rail and the adjacent projection of the seat, and means on each member for holding the clamp interlocked with the rail and projection.

6. The combination with a railway tie of cementitious material, a seat cushion thereon, a rail seat resting on the cushion and having a pair of oppositely disposed longitudinally arranged projections on its face, and a track rail resting on the seat between the projections, of holding members pivotally attached to the tie below the seat with the outer portions extending obliquely past the seat and rail flange, a clamp on each holding member adapted to hook over the rail and the adjacent projection of the seat, and means on each member for holding the clamp interlocked with the rail and projection.

In testimony whereof I affix my signature in presence of two witnesses.

LOUIS BLESSING.
